US0D1058004S

(12) **United States Design Patent** (10) **Patent No.:** **US D1,058,004 S**
(45) **Date of Patent:** **** Jan. 14, 2025**

(54) **BULB LAMP**

(71) Applicant: **SHENZHEN GUANKE TECHNOLOGIES CO., LTD.**
Shenzhen (CN)

(72) Inventor: **Qing Lan**, Shenzhen (CN)

(73) Assignee: **SHENZHEN GUANKE TECHNOLOGIES CO., LTD.**
Shenzhen (CN)

(**) Term: **15 Years**

(21) Appl. No.: **29/869,348**

(22) Filed: **Dec. 29, 2022**

(51) LOC (15) Cl. **26-04**

(52) U.S. Cl.

USPC **D26/2**

(58) **Field of Classification Search**

USPC D26/1, 2, 3, 25, 26
CPC A61L 9/20; F21K 9/232; F21K 9/238

See application file for complete search history.

(57) **CLAIM**

The ornamental design for a bulb lamp, as shown and described.

DESCRIPTION

FIG. 1 is a top perspective view of a bulb lamp showing my new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dash-dash broken lines in the drawings depict the portions of the bulb lamp which form no part of the claimed design.

1 Claim, 8 Drawing Sheets
